UNITED STATES PATENT OFFICE.

JOHN S. BRITZ, OF PORT HURON, MICHIGAN.

STAMP-CANCELER AND FOUNTAIN-BRUSH.

1,328,031.

Specification of Letters Patent. Patented Jan. 13, 1920.

Application filed April 10, 1919. Serial No. 289,024.

To all whom it may concern:

Be it known that I, JOHN S. BRITZ, a citizen of the United States, residing at Port Huron, in the county of St. Clair and State 5 of Michigan, have invented certain new and useful Improvements in Stamp - Cancelers and Fountain-Brushes, of which the following is a specification.

The invention has for an object to provide an efficient device for canceling stamps by mail sorters while distributing matter which has been passed through a canceling machine, these machines as at present constructed being found to leave uncanceled a 10 large number of stamps on letters which have been passed with others through the machine. It is also an important aim to provide a device of that character which may be readily mounted upon the pigeon-hole case ordinarily employed in the post offices of the 15 country, whereby the sorter may cancel such stamps as require it, without being compelled to leave his post at the case. It is also a further aim to provide a removable 20 marker appliance adapted to be quickly 25 filled with ink or the like.

Additional objects, advantages and features of invention will appear from the construction, arrangement and combination of 30 parts hereinafter described, and shown in the drawings, wherein:

Figure 1 is a front view of a distributing case equipped with my invention,

Fig. 2 is a detail side elevation of my invention showing a portion of the case construction,

Fig. 3 is a detail of one form of marker,

Fig. 4 is a similar view of a modified form of the marker device,

Fig. 5 is a top view thereof, with a part cut away,

Fig. 6 is a further modification of the marker device.

There is illustrated a distributing case 10, 45 of a familiar form, a case usually comprising three sections arranged to form a bay in which the distributor may stand and insert mail parcels in the pigeon-holes with facility. Centrally of the case section 11 at the 50 right hand side of the bay, I mount a stamp canceling device 12, and also one closely adjacent the left hand end 13 of the central case section, approximately as indicated at 55 14. Each of these markers is constructed in the same manner, preferably as shown in Fig. 1 as to the structural details of the

mounting, and the applicator 15 may be constructed as in any of the forms subsequently to be described. The mounting includes a base plate 16, suitably apertured for 60 the reception of mounting screws, and secured in that manner upon the top board 17 of the case. The plate 16 is provided with an ear 18 at its outer part, projected beyond the case a distance and centrally apertured 65 to receive a pivot pin 19 by which the base ear 20 of a swinging arm 21 is pivoted upon the plate, a thumb nut 22 being engaged upon the pin 19 to secure the arm 21 when adjusted at the proper angle. The arm 21 70 is preferably formed of sheet metal having the ear 20 formed integrally therewith as a lateral extension and bent upwardly into a plane at right angles to the major part of the arm 21, the outer end 23 of the arm 75 being bent outwardly to lie in a plane oblique to the plane of the arm 21 and centrally apertured to receive the conical nozzle piece 24 of a marker or ink applicator 15. The applicator 15 comprises a cylindrical 80 reservoir element 25 closed at its upper end and interiorly threaded at its lower end, the nozzle element 24 being formed with an exteriorly threaded portion 26 screwed into the open end of the reservoir 25. The nozzle 85 24 is provided with a knurled flange 27, by which it may be manipulated to effect its emplacement or removal from the reservoir, the cone 24 is hollow and its interior is enlarged toward its inner end, permitting a 90 felt wick element 28 to be inserted therethrough from the inner side as shown in Fig. 3. The base of the reservoir is provided on its upper side with a lug 29 adapted to be inserted through the apertured end 95 30 of a spring retainer arm 31. This arm 31 is secured upon the arm 21 close to the base of the latter and extended divergently therefrom, its outer end being bent so as to lie parallel to the portion 23 when the applicator 15 is coengaged between the two. The extremity of the arm 31 is bent upwardly as at 32, and normally lies so spaced from the portion 23 of the arm 21 that by inserting the cone portion 24 through the 100 apertured end of the arm 21 and pressing the upper end of the reservoir 25 inwardly against the upturned portion 32 of the spring arm 31 the applicator may be quickly forced into place and retained without requiring manipulation of any special fastening devices. 105 110

In Fig. 4 there is illustrated a modification of the applicator, in which a reservoir 35 is provided, having its closed end provided with an interiorly threaded aperture 5 through which there is engaged a screw 36 having a piston 37 thereon snugly fitted in the reservoir, the outer end of the screw being provided with a knurled head 38 by which it may be rotated to move the piston 10 37 longitudinally in the reservoir. In the outer end of the reservoir 35 there is screwed a nozzle element 39 having a knurled flange therearound by which it may be manipulated for removal and replacement, the nozzle having a plain cylindrical passage therethrough 15 in which bristles 40 are snugly packed, having located centrally therein an ink feeding tube 41 through which ink may be fed to the bristles from within the reservoir, when the screw 36 is moved. The closed end of the reservoir 35 is provided with knobs 42 thereon, at opposite sides the spring arm 31 corresponding to the arm 31 first described being bifurcated at its outer end to receive 20 25 the screw 36 therein slidably, and formed with recesses 43 in its lower side closely adjacent the inner end of the slot 44 between the furcations, the outer ends of the furcations of the arm being bent upwardly. The reservoir may also be provided with a guide lug 45 adapted to fit between the furcations 30 so as to insure the lugs 42 being in the proper position to engage in the recesses 44 when the device is put in place. This device may 35 be adjusted in the mounting in the same manner as the first described form of the applicator and may be withdrawn without requiring the use of more than one hand, as well as put in place with one hand. By its 40 use, when it is necessary to mark characters upon a package, the reservoir 35 may be grasped and pulled from its mounting and used as a marking brush, after which it may be quickly returned to its place, ready for use 45 as a stamp canceling device. When used as a marker, if a considerable amount of marking is to be done, the screw 36 may be manipulated to force ink out as required. For 50 supplying ink in canceling, it is thought that the capillary action of the liquid and the force of gravity will be sufficient to assure its proper action.

In the cancellation of a stamp the parcel bearing the stamp is grasped by one end 55 (opposite that having the stamp thereon preferably) and raised with the stamp at the upper side, until the ink applying means (felt or bristles) is engaged, the stamp being interposed. In this way the stamp is effectively canceled.

The appliance may be variously constructed within the scope of the claims without departing from the spirit of the invention.

In Fig. 6 there is shown a preferred construction of the applicator, in which the res-

ervoir 35 is used, but the nozzle element 45 screwed into the outer end thereof is formed with a central conical duct 46 located centrally of the bristles 47 in which a valve element 48 is adapted to snugly engage at 70 times. The valve 48 is fixed upon a stem 49 having threaded engagement through the closed end of the reservoir, and is provided with a flange 50 adapted to engage over the inner end of the element 46 to completely 75 close it. The valve 48 is elongated and adapted to lie loosely within the duct 46, thereby obviating necessity for complete withdrawal of the valve from the duct and serving as a guide for the valve. 80

What is claimed:

1. A device of the character described comprising a base plate adapted to be secured upon a support and having an outstanding ear, a swinging arm pivoted thereon, having an apertured outer end and a divergent spring element extending into line with the aperture of the arm, the arm and the spring being in a plane approximately at right angles to the axis of the connection 90 between the arm and the base plate, means to secure the arm at various angles to the base plate, and a marking device having an end inserted through the aperture of the arm and its opposite end engaged under said 95 spring.

2. A device of the character described comprising an arm element adjustably mounted for positioning in various angular relation to the horizontal and having an 100 outer broadened and apertured end, a spring mounted upon the inner part of the arm and extending divergently outward into line with said aperture and having an outwardly turned extremity, a marking appliance comprising a reservoir having a nozzle element adapted to be inserted through the aperture of the arm, the base portion of the reservoir and the extremity of the said spring being constructed for snap-locking engagement to 110 hold the reservoir releasably in operative position.

3. A device of the character described comprising an arm mounted adjustably for disposition at various angles to the horizontal, and having an apertured outer end, a reservoir element having a discharge nozzle, a marking material engaged in the nozzle and extending therefrom a distance, a screw engaged through the bottom of the 120 reservoir, a piston within the reservoir operable by the screw, a spring on the arm extending divergently therefrom to line with the aperture, this spring and base of the reservoir being constructed for releasable engagement to hold the reservoir in operative position. 125

4. A device of the character described comprising a supporting arm having an apertured outer end, a spring on the inner 130

part of the arm extending divergently therefrom into line with the aperture and having its extremity bent outwardly, a longitudinal slot formed in the outer end of 5 the spring, a reservoir element having a nozzle adapted to be inserted partly through the aperture of the arm, ink applying means carried by the nozzle, the base of the reservoir having means to engage in said slot to 10 hold the reservoir in a predetermined rela-

tion to the spring, said spring having recesses in its underside beside the slot, and lugs at opposite sides of the base of the reservoir adapted to engage in said recesses.

In testimony whereof I have affixed my 15 signature in presence of two witnesses.

JOHN S. BRITZ.
